OIL RECOVERY METHOD AND APPARATUS

Filed April 21, 1926

UNITED STATES PATENT OFFICE

WALTER A. LOOMIS, OF LONG BEACH, CALIFORNIA

OIL RECOVERY METHOD AND APPARATUS

Application filed April 21, 1926. Serial No. 103,448.

This invention relates to a method of oil recovery and apparatus therefor.

In oil well production is usually occurs that the flow of oil from a well is accompanied by a flow of gas, and it often happens that the flow of gas is so excessive that proper control of the well is prevented, with the result that a considerable amount of both oil and gas is wasted.

10 It is common practice to provide a structure known as a "bean", through which the oil and gas flow from the well, in an attempt to mechanically control the flow. This device is provided with a constricted orifice 15 which tends to check the flow of both fluids and to prevent an excessive escape of the lighter fractions of oil and gas. This method has not proven to be an entire success, and it is the principal object of the present invention to provide a method of oil recovery and an apparatus therefor, of the type generally shown in my Patent No. 1,554,444, entitled System for the recovery of mineral oils, which will utilize the pressure of the lighter 25 hydrocarbon fractions within the well to prevent unrestricted flow of gas from the well, and at the same time to control and stimulate the flow from the well in an automatic operation.

30 Further and extensive practice of the invention set forth in my mentioned patent, in which hydrocarbon gases capable of solution in oils or of undergoing a change of phase, are utilized for a lifting effect, under the conditions of operation, has shown not only that intelligent application of the various principles, and methods therein set forth is capable of greatly increasing oil production, but that 35 the technique and installation may be widely varied and materially modified; and also that it is, in general, worthwhile to provide each well in connection with which my invention is used, not only with means permitting a 40 practically continuous observation and control of pressure therein, but also with means, including an oil inlet or "tail" pipe which extends practically to the bottom of the well, whereby any water or sand entering the same 45 50 may be reliably withdrawn in the oil stream,

and whereby the well may be substantially prevented from flowing without control.

The present invention contemplates provision of an apparatus in a well casing which will establish oil and gas columns and will 55 cause the pressure of the lighter hydrocarbon fractions to act against and with the column of oil to prevent violent action of the oil and the gas and to produce a lifting action of the column of oil by the hydrocarbon fractions 60 under certain optimum conditions; the invention contemplating the beneficial use of light hydrocarbon fractions which liquefy under the pressure of an excessive hydrostatic head and will gasify and aerate a column of 65 liquid when released in the bottom thereof to effect an upward movement of said liquid column, said gas being accelerated by the heat energy present in an oil well of considerable 70 depth.

The invention is illustrated by way of example in the accompanying drawing, in which:

Fig. 1 is a fragmentary view in central vertical section through the apparatus with which the present invention is concerned and with parts broken away for the sake of convenience.

Fig. 2 is a fragmentary view in central vertical section through a modified form of 75 the apparatus with which the present invention is concerned.

Referring more particularly to Fig. 1 of the drawing, 10 indicates a well casing. This casing is of a desired length, and consists of a plurality of lengths of imperforate casing 11, and lengths of perforate casing 12, disposed therebeneath and in continuation thereof. Mounted upon the upper end of the casing 10 is a closure cap 13 fitted with a pipe 14 carrying a valve 15. The pipe communicates with the interior of the casing and the valve permits the introduction of a gas into the casing, or the escape of a gas therefrom, as may be desired.

The cap 13 has a central opening therethrough to receive a string of tubing 16. This string of tubing extends longitudinally and centrally of the casing.

A suitable packing collar secures and seals 100

the tubing to the cap. An outlet delivery pipe 18 is connected with the upper end of the tubing 16 and permits the withdrawal of oil which is elevated within the tubing in the manner to be hereinafter described. The tubing extends downwardly within the casing to a desired depth and is fitted at its lower end with a slip joint 19, which receives the upper end of a gas jacket 20. The gas jacket is a cylindrical tube of substantially the same sectional dimensions as the tubing 16, and forms a continuation thereof. Extending through the slip joint is an inner oil tube 21 fastened in position by a packing 15 nut 22, which engages the slip joint. It will thus be seen that the slip joint separates the string of tubing 16 from the gas jacket 20 and that communication to the interior of the string of tubing 16 is then afforded 20 through the inner oil tube 21.

The lower end of the gas jacket 20 is threaded into a coupling 23 which also receives the upper end of a tail pipe 24, which pipe is in longitudinal alignment with the 25 string of tubing 16 and forms a downward continuation thereof. The coupling also has a threaded bore receiving a mixer 25. This mixer has a Venturi passageway through it, extending longitudinally of the pipe structure and establishing communication between the tail pipe 24 and the inner oil tube 21. At 30 points around the mixer, and slightly above the point of constriction in the Venturi passageway, a plurality of outwardly and downwardly extending ducts 26 are formed through the wall of the mixer and communicate with the chamber 27, formed between the outer wall of the mixer and the circumscribing inner wall of the gas jacket 20. The tail pipe 24 may extend any desired distance 35 below the coupling 22. In some instances it has been satisfactorily extended for a distance of one thousand feet below this coupling.

The lower end of the tail pipe is formed with perforations 28, which permit an inflow of oil to the tail pipe. Interposed at a desired point in the length of the tail pipe is a Venturi throat member 39, which produces 40 a constricted orifice through which fluids must flow in passing upwardly through the tail pipe. Disposed within this orifice is an upturned nozzle 30, in communication with a central feed pipe 31. This pipe extends 45 centrally and upwardly through the tail pipe 24, the mixer 25, the inner oil tube 21 and the string of tubing 16, being thereafter suitably connected with an oil fractionator and a compressor by which it may be supplied with 50 light hydrocarbon fractions, such as propane, which have the characteristic of liquefying under excessive pressures and gasifying under lesser pressures. These hydrocarbon fractions also have the characteristic of being 55 absorbed by hydrocarbon oils under heavy

pressure and of being liberated under progressive conditions of partial pressure. The liquefied hydrocarbons may be delivered under pressure to the central feed pipe 31, or means may be provided to insure that they 70 will be constantly supplied thereto while permitting the hydrostatic head of the well to produce the pressure. In a well of a depth of substantially four thousand feet it is found that a typical pressure is approximately 2500 75 pounds to the square inch at the nozzle 30.

In order to obtain the light hydrocarbon fractions necessary for the successful operation of the present invention the delivery pipe 18 communicates with a separator 32, 80 from which the fractions may be drawn off and delivered by compressors 33 to storage tank 34, after which these fractions may be delivered to the central feed pipe 31 by a pump 35.

The gas jacket 20 is formed with a plurality of gas openings 24 which extend through the wall of the jacket at a point adjacent and beneath the slip joint 19, thus establishing communication between the casing 90 10 and the interior of the gas jacket 20.

In the form of the invention shown in Fig. 2 of the drawing, the parts are substantially identical to those indicated in Fig. 1 of the drawing, with the exception that the positions of the mixer ducts 26 and the gas inlet ducts 36 are reversed and the mixer is thus disposed above the position at which the gas inlet ducts are formed through the gas jacket 20. In this structure it will also be noted 95 that the mixer communicates directly at its upper end with the string of tubing 16, and that at its lower end it communicates directly with the tail pipe 24, which extends downwardly through the slip joint 19. In the structure shown in Fig. 2, it will, therefore, be evident that the inner oil tube 21 has been eliminated and that in the reversal of parts, the tail pipe 16 has been connected to the mixer at the point originally provided for the inner oil tube when the mixer was in its reversed position.

It will also be noted that in both forms of the invention, the inlet ducts 26 incline upwardly and inwardly through the wall of the mixer and communicate with the Venturi throat at a point above the constriction therein.

In some installations it may be desirable to connect the casings of structures similar to those shown in Figs. 1 and 2, so that a flow of gas may be effected from one casing to the other. This may be accomplished by connecting pipe 37, controlled by valves 38 with the two casings. The present invention, however, is concerned with the operation of the individual units and the manner in which oil is elevated from the well.

In the operation of the invention as shown in Fig. 1 of the drawing, it will be assumed 130

that the well casing and the tail pipe extend into a productive oil bearing stratum, in which event the oil and gas will percolate into the lower end of the casing 10, through the openings in the perforated section 12; it being characteristic of the gas to then follow a vertical path of travel along the side wall of the casing 10, while the pressure will force the oil inwardly and it will eventually find its way through the openings 28 in the tail pipe 24. By this arrangement, it will, therefore, be evident that the fluid within the tail pipe will be oil substantially free from gas and that the fluid outside of the tail pipe and confined within the casing will be a mixture of gas and oil. The mixed fluids within the casing will, therefore, be of lighter specific gravity than the liquid within the tail pipe and the levels assumed by the liquid in the tail pipe and the fluids within the casing will be materially different when the two columns are in hydrostatic balance.

An investigation of conditions in a particular well will determine this variation in level between the two columns and will make it possible to determine the point at which the gas inlet openings 36 occur, as well as the point at which the mixer 25 may be placed.

Under optimum operating conditions, the structure shown in Fig. 1 of the drawing, should be so designed that the mixture of oil and gas will normally assume the level indicated at "a",—this level occurring just below the lower edge of the gas inlet openings 24. The level of the column of oil under the operating conditions of specific gravity present should substantially intersect the openings 26 leading from the compartment 27 through the side walls of the mixer 25; this level being indicated at "b" in Fig. 1. The level of the fluid mixture as indicated at "a" should be maintained due to the pressure of the gas within the casing 10, above the level of the mixture and as confined by the casing cap 13. This pressure may be relieved by the manipulation of the valve 15, or it may be increased by introducing light hydrocarbon fractions, such as propane, into the upper end of the casing, by the valve 14 and through the pipe 15.

It is to be understood that the gas within the compartment formed by the wall of the casing and the tubing string 16, and defined at the top by the casing cap 13 and by the level of the fluid mixture as indicated at "a", is preferably a propane hydrocarbon fraction which will liquefy under pressure and may be absorbed by the oil into which it is injected, thereafter changing its physical state to a gas under conditions of reduced pressure to perform the beneficial work herein contemplated.

The gas under pressure will pass through the gas openings 24 in the gas jacket 20 and then downwardly within the compartment

27 to the openings 26 through the mixer. This gas will then encounter the liquid within the mixer and will tend to force itself upwardly through the liquid in an effort to escape. If the pressure is excessive, it will liquefy and move upwardly under the pressure until it has opportunity to expand, at which time it will begin to gasify, accompanied by ebullition and the production of a froth formed by the mixture of the oil and the gas, as it aerates the fluid particles and elevates them upwardly through the delivery pipe 18. If the pressure of the gas above the level "a" of the mixture of gas and oil should sufficiently reduce, it is evident that the mixture of gas and oil in the casing "a" would rise to a new level, generally indicated by dotted lines at "a'"; for it is to be understood that it is only the counter-pressure of the gas above the level "a" of the mixed fluids which holds the mixture of gas and oil to the level "a" below the gas inlet openings 24. The level of the mixture of gas and oil in the column will not recede to a point where the gas inlet openings 24 are uncovered, until sufficient gas has been liberated from the mixture to create an adequate counterpressure upon the mixture and again force it downward to the level "a" or therebelow. Under these varying conditions of gas pressure, it is obvious that the pumping of oil would be intermittent, and it is intended that the apparatus shall be designed so that this pumping shall be substantially continuous. This is practically insured, due to the friction head which is produced within the gas jacket 20 between the gas inlet openings 24 and the mixer 25, which will act to maintain the column of gas and oil within the casing, and the column of oil within the oil tube and tail pipe, with substantially uniform levels with relation to the conduits in which they are contained and with relation to each other. This eliminates the necessity of the use of so-called "beans" having a constricted orifice through which the fluids may flow and cause the well to operate under substantially constant flowing conditions after equilibrium has once been established.

In order to increase the production of a well after the foregoing desirable conditions of operation have been established, light hydrocarbon fractions, such as propane, are delivered to the central feed pipe 31 and conveyed to the nozzle 30 positioned within the Venturi throat 29. The relative position of this nozzle and throat to the mixer is dependent upon the degree of latent heat existing within the well and it is only necessary to insure that the nozzle is at a sufficient depth where the heat energy will properly vaporize the propane delivered through the central feed pipe without producing excessive vaporization and thus diminishing the lifting qualities of the resulting gas. After the liquid,

preferably propane, or a light hydrocarbon fraction, is injected into the bottom of the column of oil within the tail pipe, this liquid will be partially absorbed by the oil and will be partially liberated due to the heat energy present, and will tend to act by the mechanical force of the injection to raise the column of the oil, at the same time moving upwardly into gradually reduced zones of pressure, while the liquid will return to its gaseous state and act by ebullition to lower the specific gravity of the column, and at the same time to lift the column through the mixer 25 and upwardly by the aid of the gas under pressure in the casing above the level of the mixture of gas and oil to the outlet delivery pipe 18 of the well.

In the form of the invention shown in Fig. 2 of the drawing, the characteristic of the apparatus is such that the pumping action will be intermittent and the fluids pumped from the well will be emitted in alternate quantities of oil and gas, thus the pumping action will be interrupted during a period of accumulation of oil within the tail pipe 24 and the tubing 16, after which a sufficient pressure of gas above the level of the mixture of oil and gas in the casing will act to force the oil downwardly until the level of the mixture of gas and oil is below the level of the openings 36, at which time the gas under this excessive pressure will rush upwardly within the gas jacket 20 and through the opening ducts 26 in the mixer 25 to encounter a "slug" of oil standing within the mixer and within the tail pipe 16 to raise the slug of oil until the pressure is sufficiently relieved within the casing to permit the mixture of gas and oil to rise and cover the gas inlet openings 36, to a distance determined by the relative specific gravities of the mixture of gas and oil within the casing and the column of oil extending upwardly through the tail pipe 24; this, of course, being also dependent upon the gas pressure within the casing above the mixture as an additional factor.

It is to be understood that in the operation of this variation of the invention, the central feed pipe will operate to deliver the light hydrocarbon fractions to the lower end of the oil column, as previously described.

It will be understood that the greater the difference between the levels of the mixer openings 26 and of the gas inlet openings 36, the greater will be the fluctuations in gas pressure within the casing. This will also cause a greater interval between surges of oil and will cause the quantity of oil emitted at any one surge to be greater.

It will thus be seen that by the method and apparatus here disclosed, a substantially constant or fluctuating equilibrium may be established between a column of oil and a column of mixed gas and oil in a manner to cause the pressure of a gas forming one fraction of the

oil to act to elevate the oil and to prevent the premature and useless exhaustion of the gas energy, and it will further be evident that without use of external pumping means the products of the well may be utilized to elevate the oil therein in a manner to avoid waste of gas and danger of early sanding-up of the wells, and in a manner to permit the fluid pressure within the well to be at all times suitably controlled in proper relation to the successive stages of its development.

While I have shown the preferred method of carrying out my invention and preferred embodiments of apparatus therefore, it will be understood that various changes might be made in the steps of the method and the construction of the apparatus without departing from the spirit of the invention as claimed.

I claim:

1. In means for causing and controlling the flow of an oil well, a tubing string for the upward delivery of oil, a tail pipe therebelow, extending substantially to the bottom of a well, an intermediate organization comprising a mixer surrounded by a shell, said mixer and shell being apertured at different levels, means for supplying pressure fluid to the mixer, and a pipe for the downward and interior delivery of a light hydrocarbon to a level below said mixer.

2. A method of oil production in which a light hydrocarbon mixture, kept in liquid phase by high pressure, is fed into a column of heavier oil near the bottom thereof, and in which a gas containing a lighter hydrocarbon is admitted to said column at a higher level.

3. A method of oil production in which a light hydrocarbon mixture, kept in liquid phase by high pressure, is fed into a column of heavier oil near the bottom thereof, and in which a gas containing a lighter hydrocarbon is admitted to said column at a higher level, internal and external pressures at the last mentioned level being substantially the same.

4. In the elevation of oil from a well, maintaining an accumulated column of oil therein in communication, at an intermediate level and at a low level, with a derived column of oil provided with an outlet at the top of the well, periodically building up upon said accumulated column a gas pressure sufficient to elevate a slug of oil in said derived column above said intermediate level of communication while incidentally lowering the level of said accumulated column sufficiently to deliver gas, at said intermediate level only, into said derived column, said gas being initially delivered thereto at substantially the same pressure as then exists at the same level within said derived column to create an upward surge in said derived column, and effecting a reduction in the gas pressure upon said ac-

cumulated column to intermittently cut off said gas delivery.

5. A method of the general character defined in claim 4, in which said accumulated column and said derived column both extend substantially to the bottom of said well.

6. A method of the general character defined in claim 4, in which the mentioned upward surge is supplemented by the separate 10 introduction of a light hydrocarbon below said intermediate level.

7. In the elevation of oil from a well, producing a surging flow with slugs of oil from an oil well by maintaining communication 15 at two levels between a derived column and an accumulated column of oil therein, and so periodically varying a gas pressure upon the said accumulated column as to produce differences in the height of said columns and 20 to admit gas intermittently to said derived column at said intermediate level.

8. A method of elevating oil from a well which consists in creating a column of heavy gravity oil and a column of lighter gravity 25 hydrocarbons comprising a mixture of said oil and gaseous fractions thereof, thereafter causing the pressure of gaseous fractions liberated from the mixture to force said gas into the column of oil to elevate the same and then 30 projecting a stream of light hydrocarbon fractions into the bottom of the column of oil in liquid phase to cause elevation of said column of oil as said light hydrocarbon fractions change from a liquid to a gaseous state.

35 In testimony whereof, I have hereunto set my hand at Los Angeles, California, this 15th day of April, 1926.
